UNITED STATES PATENT OFFICE.

JOHN E. LAMBERT, OF DETROIT, MICHIGAN.

DESIGN FOR A VAPOR-BURNER.

SPECIFICATION forming part of Design No. 34,172, dated March 5, 1901.

Application filed February 7, 1901. Serial No. 46,446. Term of patent 14 years.

To all whom it may concern:

Be it known that I, JOHN E. LAMBERT, a citizen of the United States, residing at Detroit, in the county of Wayne and State of Michigan, have invented and produced a new and original Design for Vapor-Burners, of which the following is a specification, reference being had to the accompanying drawings, forming a part thereof, in which—

10 Figure 1 is a side elevation of the vapor-burner. Figs. 2 and 3 are front and rear elevations, respectively. Fig. 4 is a plan view thereof.

15 As shown in the drawings, the leading or material feature of the design consists in giving to the upper portion of the burner the appearance of having a neck by means of a circular flange *a* around the base of the

burner-head *A*, and a corresponding flange *b* a slight distance below on the body *B*, so 20 that a portion of the body of the burner is embraced between the two flanges *a* *b* and gives to the burner the appearance of having a neck portion *c* below the burner-head.

Having thus fully described my invention, 25 what I claim as new, and desire to secure by Letters Patent, is—

The design for a vapor-burner substantially as herein shown and described.

In testimony whereof I affix my signature 30 in presence of two witnesses.

JOHN E. LAMBERT.

Witnesses:

OTTO F. BARTHEL,
LEWIS E. FLANDERS.
